UNITED STATES PATENT OFFICE

MONTAGU BLATCHFORD, OF HALIFAX, ENGLAND, ASSIGNOR TO JOSEPH WILD & CO., OF NEW YORK CITY.

DESIGN FOR A CARPET-PATTERN.

Specification forming part of Design No. 5,706, dated March 26, 1872.

Specification describing an Improved Design for Carpet, invented by MONTAGU BLATCHFORD, of Halifax, in the county of York, England.

The accompanying photographic illustration fully represents my new design.

This invention relates to a new design of an ornamental rosette and of a curvilinear four-sided figure, and in their combination with each other, when applied to a carpet or other fabric.

The rosette A has convex borders a a, and four shields, B, piercing the same, its center containing a smaller rosette, b, while the shields B are ornamented by scroll d, as shown. The four-sided figure C has concave sides, and is beveled at the corners with projecting leaves e e at the corners.

I claim as my invention—

1. The design of the rosette A having the shields B, as shown.
2. The design of the figure C, as shown.
3. The design for a carpet, consisting of the combination of the figures A, B, and C, as shown.

MONTAGU BLATCHFORD.
